UNITED STATES PATENT OFFICE.

MARIANO ZALVIDEA, OF MANILA, PHILIPPINE ISLANDS.

HEMP AND PINA STRIPPING MACHINE.

Application filed December 27, 1923. Serial No. 683,067.

To all whom it may concern:

Be it known that I, MARIANO ZALVIDEA, a citizen of the Philippine Islands, owing allegiance to the United States, residing at 5 Manila, Philippine Islands, have invented certain new and useful Improvements in Hemp and Pina Stripping Machines; and I do hereby declare that the following is a full, clear, concise, and exact description of 10 the invention, such as will enable others skilled in the art to which it appertains to make and use the same.

This invention relates to improvements in fiber stripping machines and particularly to 15 improvements over that type of machine for use in stripping fiber from hemp pulp and pina leaves described and claimed in my pending application for United States Letters Patent Serial Numbered 598,007 including means for transmitting rotary motion to the fiber removing and carrying wheel and a novel arrangement of stripping knife and table therefor, such knife being adjustable to different positions for facilitating 25 the disengagement or removal of fiber from the pulp and leaves treated by the machine.

It is likewise an object of the invention to provide a novel form of control for the 30 machine; whereby the transmission of driving motion to the wheel, the release of the braking means therefor and the movement of the knife or table to proper position with respect to the adjustable knife will be simultaneously or collectively effected by operation of but a single control device, thus rendering it possible for an operator to quickly and conveniently control the machine.

40 Other objects will be in part obvious and in part pointed out hereinafter.

In order that the invention and its mode of operation may be readily understood by persons skilled in the art, I have, in the 45 accompanying illustrative drawings and in the detailed following description based thereon set out one embodiment of the same.

In these drawings:

Figure 1 is a side elevation of the improved machine;

Figure 2 is a vertical transverse section therethrough;

Figure 3 is a top plan of the same;

Figure 4 is an elevation of the machine

viewed from the opposite side shown in the 55 Figure 1;

Figure 5 is an enlarged fragmentary detail in perspective showing the mounting of the stripping knife;

Figure 6 is a horizontal section taken on 60 the line 6-6 of Figure 4 looking in the direction in which the arrows point; and,

Figure 7 is an enlarged fragmentary detail in section showing the construction of the yieldable connecting device. 65

Having more particular reference to the drawings, in connection with which like characters of reference will designate corresponding parts throughout, the improved machine may be stated to comprise a supporting frame consisting of a base portion 1 and supporting standards 2, said standards converging at their ends and having a circular bearing sleeve 3 formed at said ends, while a shelf or bracket 4 is arranged between the intermediate portions of the standards and is adapted to have a bearing bracket 5 secured thereto through the medium of bolts 6 passing through the flanged feet of said bracket and through adjacent portions of said plate 4, thus immovably securing the same in position with respect to these standards. 70

A fiber carrying wheel 7 is provided the 75 machine and is adapted to have the hub portion 8 thereof rotatably engaged with a bearing pin or axle 9, which axle it will be noted, has one end thereof formed with a tapered bearing extremity removably engaged in the concentric opening of the bracket 5, whereupon a locking nut 10 is turned into engagement with the screw threaded extremity and thus secures said axle in an immovable position with respect to the standards 2. Oilways or ducts 11 are 80 preferably formed in the axle 9 and communicate with the outermost bearing surfaces thereof, an oil cup or similar device 12 being engaged with the inner end of the bearing 10 and communicating with the adjacent 85 end of the longitudinal duct 11. In this connection, it will be noted that the outer end of bearing pin or axle 9 is formed with a flanged head 13 and furthermore, that a 90 bearing bushing 14 is arranged within the hub portion 8 of the wheel 7 and is adapted to be engaged over the adjacent portion of the axle; An arm 15 having an enlarged

2
screw threaded inner end 15' is turned into engagement with a concentrically arranged screw threaded opening adjacent the hub portion 8 of the wheel 7 whereby to enclose 5 the outer end of the axle or bearing pin 9.

The inner side of the wheel 7 has a plurality of parallel circumferentially extending grooves 16 formed therein which are adapted to be engaged by the ribbed peripheral portion of a frictional power transmitting pulley 17 mounted upon an axle 18 rotatably supported upon anti-frictional bearing devices 19 within a movably supported bearing bracket 20. This bearing bracket 20 is slidably received between guides 21 formed upon adjacent portions of the lower parts of the standards 2 and is carried on a vertically extending arm 21 pivotally connected to the same as at 22; the lower end of said arm being pivotally connected as at 23 to a lever 24 pivotally mounted upon a bearing bracket 25 secured to the base 1.

Upon the outer end of the shaft 18 there 25 is mounted a power transmitting connection, such for example as a sprocket wheel, herein shown and designated by the numeral 26, said sprocket wheel being adapted to have a chain engaged about the same and extending 30 from a suitable source of power, not shown.

Brake means are provided the wheel 7 and comprise flexible brake band 27 engaged over a portion of a periphery of the wheel 35 and having one end of the same pivotally connected by a strap 28 to a portion of the machine stand 1 as indicated at 29, while the opposite end of such brake band is connected to a strap or similar device 30 which 40 in turn is pivotally connected as at 31 to a lever 32 pivotally mounted upon a bracket 33 also mounted upon the base 1; the opposite portion of such lever 32 being extended to a point in proximity to the free portion 45 of the lever 24, for a purpose which will be presently described.

Pivotally connected in the upper end of a bearing bracket 34 arranged upon the stand 1 is a lever 35, which as will be noted, extends transversely across the upper side of said base and carrying a pedal 36 upon its free end. This lever 35 has its intermediate portion directly over the free ends of the several levers 24 and 32 and in consequence, 50 with depression, such adjacent free portions of said levers will be engaged and in consequence, pivotal movement imparted to the same.

In order that the pedal carrying portion 60 of the lever 35 will be normally held in its uppermost position, a contractile coiled spring 37 is connected at one end to a fixed portion of one of the standards 2 while the opposite or lower end thereof is connected 65 to adjacent portions of the free end of the

levers 24 and 32, portions of which, as hereinbefore stated, underlie the intermediate portion of the lever 35. Hence, an upward pull will be normally imparted to the free end of the levers 24 and 32 by the coil 70 spring 37, causing the same together with the bearing bracket to be normally retained in their uppermost positions together with the pedal carrying end of the lever 35.

Rotatably mounted in the bearing sleeve 75 3, hereinbefore described is a shaft 38 adapted to be placed under tension, at times, by means of a coil spring 39 engaged about a portion of the same and arranged within said bearing sleeve 3, one end of the spring 80 being connected to an adjacent portion of the bearing sleeve and the opposite end of such spring being connected to a portion of the shaft 38. An arm 40 is fixedly secured to one end of the shaft 38 and is adapted 85 to impart oscillatory motion thereto thru the medium of a connecting rod 41 connected to the same by way of a spring or yieldable coupling 42 pivotally connected to its outer end as at 43. The lower end of 90 this connecting rod 31 is extended downwardly into pivotal engagement with an intermediate portion of the transversely disposed lever 35 and in consequence, with depression of the pedal 36 carried thereon, a 95 downward pull will be imparted to the connecting rod 41 and in consequence, the desired rocking movement will be imparted to the shaft 38.

As shown in the Figure 7, the yieldable 100 coupling 42 comprises an elongated cylindrical casing having its upper end partially closed as indicated at 42' whereby to engage the headed end of the arm employed in the pivotal connection 43, while the lower end of said casing is open and internally screw threaded in order that a threaded closure plug 42^a may be turned into engagement therewith. The upper portion of the rod 41 is passed thru the plug 42^a into the casing whereat it is connected to the upper end of a coiled spring 42^b arranged within such casing. In this manner, it is obvious that a yieldable or spring connection 105 will be effected between the arm 40 and the lever 35.

Also fixedly mounted upon said shaft 38, that is, upon the opposite portion thereof, is a bracket arm 44 carrying a table 45 upon the outer end thereof, which table is adapted 110 to receive the hemp or pina leaves to be treated by the machine.

To provide means for stripping the fiber 115 from the hemp or pina leaves, a slotted arm 46 is extended obliquely upward from the upper converging portions of the standards 2 and is adapted to receive the bolt 47 of a knife securing and holding bracket 48 there-through, a knife or blade 49 being suitably secured to said holder and adapted to have 120 125 130

its position with respect to the table 45 suitably varied by proper adjustment of the bolt 47.

Laterally extending fiber carrying arms 50 are secured to the circumferential portions of the wheel 7 in equidistant spaced relation and as will be understood, serve as means for permitting the attachment of the stalks or leaves thereto during a fiber stripping operation such attachment being effected by impaling portions of the stalks or leaves upon the fiber carrying arms 50 or by slitting portions of the stalks or leaves and twisting the same thereabout in a manner to effect connection with the arms. The arms 50 shown in this particular embodiment are illustrated as being of triangular configuration, although it is of course to be borne in mind that the specific design of such arms may be widely varied, such as conditions or preference may dictate.

The operation of my improved machine may be reviewed as follows:

The knife 49 is first properly positioned 25 in the slotted bracket arm 46 so that with movement of the table 45 in operative position therewith, such knife will function to effectually remove the pulp from the hemp or pina leaves being treated. With proper 30 adjustment of the knife effected, the foot of the operator is engaged with the pedal 36 whereby to depress the same, causing downward movement of the transversely disposed lever 35 and in consequence, imparting 35 downward thrust to the free portions of the several levers 24 and 32. Such downward movement of the levers 24 and 32 will cause collective movement of the frictional driving pulley 17 so as to engage the circumferentially grooved portion 16 of the wheel 7 and cause the slackening of the brake band 27 engaged over the peripheral portion of 40 said wheel 7, releasing the same and permitting it to have free rotation under influence 45 of the rotatably driven power transmitting pulley 17. Simultaneously, a downward pull will be imparted to the lever or arm 40, causing the table 45 to be moved upwardly into operative position with respect to the 50 knife blade 49. Thus, when one end of the hemp or pina leaves to be stripped is engaged with an adjacent arm 50 carried on the wheel 7, such matter will be drawn over the table 45 by the knife blade 49, whereby 55 excess or waste matter will be removed therefrom, leaving only the fibers which are desired. When the wheel 7 has rotated sufficiently to cause the matter being stripped of the fiber to pass entirely by the knife blade 49, 60 the pedal 36 is immediately released, whereupon it will return to its normal uppermost position by reason of the upward pull imparted thereto by the contractile coil spring 37 connected at its lower end to the free ends 65 of the levers 24 and 32. Simultaneously

with such movement of the pedal 36 to its normal uppermost position, the arm 21 carrying the bearing bracket 20 will be likewise moved upwardly so as to disengage the frictional pulley 17 from the grooved inner side of the wheel 7, thereby discontinuing the transmission of rotary motion to said wheel. Likewise, at this time, the lower end of the spring 37 which is also connected to the free end of the lever 32 will cause the same to be drawn upwardly, thus moving the opposite end downwardly and tightly engaging the flexible brake band 27 over the peripheral portion of the wheel 7, thus braking the same and causing it to immediately cease 75 rotation. Also, with release of the pedal 36, the arm 40 will be returned to its normal position, thus permitting the table 45 to be lowered from engagement with the knife 49, whereupon an additional quantity of 80 hemp pulp or pina leaves may be engaged thereover for stripping by passage of the same by the knife.

From the foregoing, it will be seen that I have provided a hemp or pina leaf stripping 90 machine which is exceedingly simple in operation and control, the arrangement of the foot actuated lever 35 being such as to effect collective or simultaneous control of the transmission of rotary motion to the wheel 7 95 and the release of the braking means therefor as well as movement of the table 45 into operative position with respect to the previously properly adjusted knife 49. With release of the foot actuated lever 35, the parts controlled thereby will immediately return to their normal positions, the brake band 27 exerting a braking force upon the peripheral portion upon the wheel 7 and immediately seeking its rotation.

Manifestly, the construction shown is capable of considerable modification and such modification as within the scope of my claims, I consider within the spirit of my invention.

I claim:

1. A machine of the character described comprising in combination with a supporting frame, a fiber pulling and carrying wheel rotatably mounted thereon, movably supported means for transmitting rotary motion to said wheel, a knife supported in the upper end of said frame, a table pivotally supported on the frame in proximity to said knife, and means for simultaneously moving the motion transmitting means into engagement with the wheel and the table into operative position with respect to said knife.

2. A machine of the character described comprising in combination with a supporting frame, a fiber pulling and carrying wheel rotatably mounted thereon, movably supported means for transmitting rotary motion to said wheel, a knife supported in

the upper end of said frame, a table pivotally supported on the frame in proximity to said knife, braking means normally engaged with the peripheral portion of said wheel, and 5 means for simultaneously moving the motion transmitting means into engagement with the wheel, the table into operative position with respect to said knife and releasing the brake means from engagement with the 10 peripheral portion of said wheel.

3. A machine of the character described comprising in combination with a supporting frame, a fiber pulling and carrying wheel rotatably mounted thereon, laterally 15 extending arms upon said wheel, movably supported means for transmitting rotary motion to the wheel, a knife adjustably supported in the upper end of the frame, a table pivotally supported on the frame in 20 proximity to said knife, and means for simultaneously moving the motion transmitting means into engagement with the wheel, the table into operative position with respect to said knife and releasing said 25 braking means from a peripheral portion of the wheel.

4. A machine of the character described comprising in combination with a supporting frame, a fiber pulling and carrying 30 wheel rotatably supported thereon, a rotatable power transmitting pulley movably supported on the frame and engageable with said wheel, a knife adjustably supported in the upper end of said frame, a table pivotally supported upon the frame in proximity 35 to said knife, and means for collectively moving said power transmitting pulley and table.

5. A machine of the character described 40 comprising in combination with a supporting frame, a fiber pulling and carrying wheel rotatably mounted thereon, a rotatable power transmitting pulley movably supported on the frame, and engageable 45 with said wheel, a knife adjustably mounted in the upper end of said frame, a table pivotally supported upon the frame and ar-

ranged in proximity to said knife, braking means for said wheel normally engaged with its peripheral portion, and manually 50 operable means for simultaneously effecting movement of the power transmitting pulley into engagement with the wheel, pivotal movement of the table into operative position with respect to the knife and disengagement of the braking means from the 55 peripheral portion of said wheel.

6. A machine of the character described comprising in combination with a frame, a bearing bracket fixedly supported upon the 60 intermediate portion of such frame, a fiber pulling and carrying wheel rotatably supported by the bearing bracket, said wheel having the inner side of the rim thereof formed with circumferentially extending 65 grooves, a second bearing bracket, a shaft rotatably mounted in said second bearing bracket, a frictional wheel mounted on said shaft having the peripheral portion thereof ribbed and engageable with the grooves 70 upon the inner side of the rim of said wheel, means for movably supporting said second bearing bracket with respect to the frame, a knife adjustably supported in the upper 75 end of said frame, a table pivotally supported on the upper end of the frame in proximity to said knife, an arm fixedly connected to said table and adapted to rock the same, a flexible braking band fixedly connected at one end to the frame and engaged over the peripheral portion of said wheel, an actuating lever connected to the free 80 end of said braking band, and means for simultaneously moving the frictional wheel into engagement with the grooved inner side of the first wheel rim, pivotally moving the table into operative position with respect to said knife and disengaging the flexible 85 braking means from the peripheral portion of said first wheel.

In witness whereof I have hereunto set my hand.

MARIANO ZALVIDEA.
